UNITED STATES PATENT OFFICE.

THOMAS F. BARTON, OF CHICAGO, ILLINOIS.

GRAIN-DOOR FOR CARS.

No. 872,785.

Specification of Letters Patent.

Patented Dec. 3, 1907.

Application filed March 1, 1907. Serial No. 360,017.

To all whom it may concern:

Be it known that I, THOMAS F. BARTON, a citizen of the United States, residing at Chicago, county of Cook, State of Illinois, have 5 invented a certain new and useful Improvement in Grain-Doors for Cars, and declare the following to be a full, clear, and exact description of the same, such as will enable others skilled in the art to which it pertains 10 to make and use the same, reference being had to the accompanying drawings, which form a part of this specification.

My invention relates in general to railroad cars and more particularly to grain doors for 15 freight cars.

It is necessary that the doors of grain cars should securely close the door openings so as to prevent the grain from leaking out of the cars, and at the same time readily open to 20 permit the cars to be unloaded. It is therefore desirable that grain doors should be provided with wickets or panels controlling openings through the doors in order that the pressure of the grain upon the inner surfaces 25 of the doors may be relieved by permitting the grain to be first discharged through the openings controlled by the wickets or panels, thereby rendering it possible to easily open the doors. 30 The primary object of my invention is to provide a grain car door with a movable wicket or panel located upon the inner surface of the door so as to be held tightly over the opening which it controls by the pressure 35 of the grain.

A further object of my invention is to provide a grain door for cars having a movable wicket which will be simple in construction, inexpensive in manufacture, and efficient in 40 use.

My invention may be generally described as comprising a vertically movable wicket located upon the inner surface of a grain door and controlling an opening extending substantially the entire width of the door, pairs of guides secured to the outer and inner surfaces of the door between which the wicket reciprocates, a link pivotally connected at its lower end to the wicket and at its upper end to a crank arm on the inner end of an oscillatory stub shaft extending through the door, a lever fixed upon the outer end of the stub shaft by means of which the shaft is rocked and the wicket thereby elevated to 55 uncover the opening in the door and permit the grain to be discharged therethrough.

My invention will be more fully described hereinafter with reference to the accompanying drawing in which the same is illustrated as embodied in a convenient and practical form, and in which Figure 1 is an elevational view of the inside of a grain door provided with my improvement; Fig. 2 a sectional view on line 2—2 Fig. 1; Fig. 3 a horizontal sectional view on line 3—3 Fig. 1; and Fig. 4 a vertical sectional view on line 4—4 Fig. 1. 60 65

The same reference characters are used to designate the same parts in the several figures of the drawings.

Reference letter A designates a grain door 70 of suitable construction for use on freight cars. The door is shown as comprising transverse boards united by vertical battens A' and A³ at sides of the door and a central vertical batten A². One of the transverse 75 boards preferably the second above the lower edge of the door, is cut out between the inner edges of the battens A' and A³ thereby forming an opening a through the door of substantially the width of the door. 80

B indicates a wicket or panel located upon the inside of the door and of a height to overlap at its top and bottom the opening a through the door. The wicket is of a length slightly less than the distance between the 85 inner edges of the battens A' and A³, as clearly shown in Figs. 1 and 3. The wicket is preferably made of sheet metal.

C', C², and C³ designate guides secured to the outer surface of the door and off-set 90 within the opening a so as to form guiding surfaces for the wicket flush with the inner surface of the door, as clearly shown in Figs. 2 and 4. The guides C', C², C³ may be conveniently formed of flat strips of metal 95 bolted at their upper and lower ends to the door.

D' and D³ indicate guides secured to the inner surface of the door and spaced apart from the guides C' and C³ distances slightly 100 greater than the thickness of the wicket so that the wicket will be guided in its movements to open and close the opening a. The guides D' and D³ are preferably circular in cross-section in order to obviate the danger 105 of grain becoming wedged between the guides and the inner surface of the wicket. D² indicates an intermediate guide secured to the inner surface of the door and preferably formed of a flat metal strip having holes d² 110 therethrough to permit the free passage of grain through such guide and thereby pre-

vent the grain from becoming wedged between the guide and the door. The inside guides D' , D^2 , D^3 are provided with perforated ears at their lower ends which overlie 5 and are secured to the board of the car door immediately below the opening a , the same bolts which secure the lower ends of the outside guides to the door being preferably extended through the holes in the ears on the 10 lower ends of the inside guides. The upper ends of the inside guides are also provided with ears having holes through them which preferably align with the holes in the upper ends of the outside guides so that the same 15 bolts may be used to secure the upper ends of the pairs of inside and outside guides to the door.

E designates a bracket secured to the inner surface of the wicket intermediate of its 20 ends by any suitable fastening devices, such for instance as rivets e . The bracket E is provided with a saddle or yoke E' surrounding the guide D^2 and which moves relatively to such guide during the raising or lowering 25 of the wicket. The bracket E is provided with a stud e' which preferably projects inwardly from the saddle E' and upon which is pivotally supported the lower end of a link F. The lower end of the link F may be conveniently provided with a hole through which 30 the stud e' extends, the link being retained around the stud by a cotter pin f extending through a hole in the stud.

The upper end of the link F is pivotally 35 connected to the end of a crank arm G fixed upon the inner end of a stub shaft H. The stub shaft H extends through the door and is mounted to rock therein. Bearing plates h' and h^2 are preferably secured to the inner 40 and outer surfaces of the door around the stub shaft to form bearings in which such shaft oscillates. K designates a lever fixed upon the outer end of the stub shaft H and located adjacent the outer surface of the 45 door. The crank arm G and lever K may be conveniently secured to the opposite ends of the stub shaft by means of square openings through which the square ends of the stub shaft extend.

50 The operation of my invention is as follows: The weight of the wicket normally causes the same to occupy its lowered position in which it closed the opening a through the door. It will be noticed that the upper 55 and lower edges of the wicket overlie the inner surface of the door above and below the opening therethrough thereby securely preventing the leakage of grain. The ends of the wicket terminate short distances away from the inner edges of the battens A' and A^3 to prevent the wicket binding against the battens during its movement. The flat outside guides C' and C^3 serve to close the spaces between the side edges of the wicket and the adjacent 60 edges of the battens, thereby preventing 65

leakage of grain around the sides of the wicket. When it is desired to relieve the pressure of grain upon the inner surface of the door in order that the door may be opened, the lever K is pressed downwardly 70 thereby rocking the stub shaft H and elevating the wicket B so that the opening a through the door is uncovered permitting the grain to be discharged through such opening and relieving the pressure of grain upon the 75 inner surface of the door. The leverage is such that comparatively little power need be exerted on the lever K to effect the raising of the wicket. When the inner surface of the door is not engaged by grain the weight of 80 the wicket automatically returns the same into its lowered position to close the opening thereby obviating any danger of the wicket being opened when the grain is loaded into the car.

85 From the foregoing description it will be observed that I have invented an improved grain door for cars comprising a wicket located upon the inner surface of the door and thereby retained by the pressure of the grain 90 closely over the opening through the door, the wicket being provided with guides for efficiently directing its movements and with means for raising the same which can be actuated from the exterior of the car.

95 While I have described more or less precisely the details of construction, I do not wish to be understood as limiting myself thereto, as I contemplate changes in form, the proportion of parts, and the substitution 100 of equivalents, as circumstances may suggest, or render expedient without departing from the spirit of my invention.

Having now fully described my invention, what I claim as new and desire to secure by 105 Letters Patent is:

1. The combination with a car grain door of a vertically movable wicket located on the inner surface of the door and controlling an opening therethrough, pairs of guides secured to the outer and inner surfaces of said door between which said wicket is adapted to slide, and means extending to the outside of the car door for raising said wicket to 110 uncover the opening through the door.

115 2. The combination with a car grain door of a vertically movable wicket located on the inner surface of the door and controlling an opening therethrough, a vertical guide secured to the inner surface of the car door 120 between which and the inner surface of the door said wicket is adapted to slide, a saddle secured to the inner surface of said wicket and extending around said vertical guide, a link pivotally connected at its lower end to 125 said saddle, an oscillatory stub shaft extending through said door, a crank arm fixed upon the inner end of said shaft to which the upper end of said link is pivotally connected, and a lever fixed to the outer end of said 130

shaft for raising said wicket to uncover the opening through said door.

3. The combination with a car grain door of a vertically movable wicket located on the 5 inner surface of the door and controlling an opening therethrough, guides secured to the outer surface of said door and off-set inwardly within said opening to form guide surfaces for said wicket flush with the inner 10 surface of said door, coöperating guides secured to the inner surface of said door, and means extending to the outside of the car door for raising said wicket to uncover the opening through the door.

15 4. The combination with a car grain door of a vertically movable wicket located on the inner surface of the door and controlling an opening therethrough, guides secured to the outer surface of said door and off-set inwardly 20 within said opening to form guide surfaces for

said wicket flush with the inner surface of said door, coöperating guides secured to the inner surface of said door, a saddle secured to the inner surface of said wicket extending over the central inner guide, a link pivotally connected at its lower end to said saddle, an oscillatory stub shaft extending through said door, a crank arm fixed upon the inner end of said shaft to which the upper end of said link is pivotally connected and a lever 25 fixed to the outer end of said shaft for raising said wicket to uncover the opening of said door.

In testimony whereof, I sign this specification in the presence of two witnesses.

THOMAS F. BARTON.
